(57) **CLAIM**

We claim an ornamental design for a modular adjustable clamp, as shown and described.

DESCRIPTION

FIG. 1 is a perspective front view of the modular adjustable clamp;

FIG. 2 is a perspective rear view thereof;

FIG. 3 is a top plan elevation view thereof;

FIG. 4 is a right side elevation view thereof;

FIG. 5 is a front elevation view thereof;

FIG. 6 is a right side elevation view thereof;

FIG. 7 is a back elevation view thereof; and,

FIG. 8 is a bottom plan view thereof.

The broken lines that illustrate portions of the modular adjustable clamp form no part of the claimed design.
